[57] CLAIM

The ornamental design for a triangular-shaped slide, as shown and described.

DESCRIPTION

FIG. 1 is a perspective view of a triangular-shaped slide showing my new design in use;

FIG. 2 is an enlarged top plan view thereof;

FIG. 3 is a bottom end view thereof as viewed in FIG. 2;

FIG. 4 is a top end view thereof as viewed in FIG. 2;

FIG. 5 is a side edge view thereof as viewed in FIG. 2; and,

FIG. 6 is a bottom plan view thereof.

The broken line showing of fragmented furniture is for illustrative purposes only and forms no part of the claimed design.
